(57) **CLAIM**

The ornamental design for a shoe outsole, as shown and described.

DESCRIPTION

FIG. 1 is a front perspective view of a shoe outsole showing our new design;

FIG. 2 is a rear perspective view thereof;

FIG. 3 is a second front perspective view thereof;

FIG. 4 is a second rear perspective view thereof;

FIG. 5 is a side view thereof;

FIG. 6 is a second side view thereof; and,

FIG. 7 is a bottom view thereof.

The broken lines immediately adjacent to the shaded area represent unclaimed boundaries of the design. The broken lines showing the remainder of the shoe are for environmental purposes only and form no part of the claimed design.

1 Claim, 7 Drawing Sheets(56)
